UNITED STATES PATENT OFFICE.

ARTHUR C. TUNISON, OF LOS ANGELES, CALIFORNIA.

DEEP-WELL PUMP.

Application filed April 9, 1924. Serial No. 705,379.

To all whom it may concern:

Be it known that I, ARTHUR C. TUNISON, a citizen of the United States, residing at Los Angeles, in the county of Los Angeles and State of California, have invented certain new and useful Improvements in Deep-Well Pumps, of which the following is a specification.

This invention relates to pumps for deep wells, and has for one of its objects to provide an apparatus of this character which will be simple in construction, comparatively inexpensive to manufacture and install, and more efficient in use than those which have 10 been heretofore proposed.

In operating wells, such for example as oil wells, at depths of five thousand feet or more, where the well known type of oil well pump, employing sucker rods, is used, much 20 difficulty, annoyance and expense is encountered, due to inherent defects in sucker rods.

These rods frequently crystallize and break, thereby causing considerable loss in both time and money in repairing the damage, and in wells of the depth mentioned, the operation of the pumps is more or less hampered, due to the elasticity of the rods themselves. In a well of five thousand feet, for example, the sucker rods will stretch as 25 much as three feet from their own weight on each working stroke, and the operation of the pumps is thereby rendered more or less uncertain. This elasticity or stretching is greatly affected by the speed of the stroke, 30 since the faster the rods are reciprocated, the greater will be the elasticity, and therefore the speed is more or less limited.

In order to overcome these defects and to 40 provide a deep well pump which will operate more efficiently, the present invention contemplates the provision of a pump which does not employ sucker rods, but in which, on the other hand, the lifting force is supplied by fluid, such as oil under pressure, 45 which is supplied to one or more pump units located at various depths in the well casing, which units comprise suitable fluid pressure actuated pistons and valves for controlling the same. Suitable apparatus is also provided at the surface for supplying the necessary pressure to the operating fluid.

With the above and other objects in view, which will appear as the description proceeds, the invention consists in the novel 5 details of construction and combinations

and arrangements of parts, more fully hereinafter disclosed and particularly pointed out in the appended claims.

Referring to the accompanying drawings forming a part of this specification, in 60 which like reference characters designate like parts in all the views;

Figure 1 is a diagrammatic sectional elevational view of the pumping apparatus for a deep well, such for example as an oil well, 65 constructed in accordance with the present invention;

Fig. 2 is an enlarged vertical sectional view of the principal working parts of the pump;

Fig. 3 is a top plan view of the valve sleeve which controls the fluid pressure flow to and from the pump piston;

Fig. 4 is a top plan view of the valve stem or rod; and,

Fig. 5 is an inverted plan view of the guiding plug which is mounted in the lower end of the piston plunger and through which the valve stem passes.

Referring more particularly to the said 80 drawings the numeral 10 indicates the well casing, which is inserted in the well bore and advanced as the bore descends, as is well known. The pump barrel 11 which comprises a metal tube or pipe of somewhat 85 smaller diameter than the casing 10, is introduced into the latter and lowered to the required depth. The said barrel is spaced from the walls of the casing 10 and its lower end suitably packed by means of the packing ring 12, thereby providing an annular space or chamber 13 between the two which serves as a conduit for conducting the pressure fluid from the surface to the operating parts of the pump.

Mounted within the barrel 11 and suitably spaced therefrom by a spacing ring or member 14, is the pump cylinder 15, which may likewise comprise a metallic tube or pipe of somewhat lesser diameter than the 100 barrel 11, whereby there is provided a second annular space or chamber 16, through which the oil from the well may be raised when the pump is operated, as will appear more fully below.

The lower end of the barrel 11 is closed by a plug member 17 which is provided with a passage 18 therethrough, which passage is controlled by means of a suitable check valve diagrammatically indicated at 19. The 110

walls of the pump cylinder 15 are provided adjacent the lower end of the said cylinder with suitable perforations 20, whereby communication is afforded between the interior 5 of the lower portion of the said cylinder and the annular space 16, and immediately above the said perforations, the said cylinder is provided with a closing plug 21, which has a passage 22 controlled by the valve 23 carried 10 by the lower end of the valve rod or stem 24.

The said pump cylinder 15 is also provided with suitable inlet passages 26, leading from the annular space 13 to the interior of the said cylinder, which latter is also provided 15 with a plurality of outlet passages or bores 27, affording communication between the interior of the said cylinder and the annular space 16.

Slidably mounted within the pump cylinder 15 in operative position relative to the bores 26 and 27 is a valve sleeve 28, preferably comprising a tube member, the walls of which are perforated adjacent its upper end as indicated at 29, to provide inlet bores or 28 openings for the actuating fluid, and which sleeve is provided below the said bores or openings 29 with the spider arms 30 which support the central valve stem guide 31, as will be clear from Figs. 2 and 3.

30 The exterior surface of the valve sleeve 28 is preferably provided with suitable packing rings 32, affording a fluid tight joint with the walls of the pump cylinder, and the said sleeve is also provided with an 35 expansion ring 33 which normally presses outward against the walls of the cylinder, and which, at a certain point in the stroke of the valve sleeve, enters an annular groove 34 formed in the cylinder walls, whereby 40 the said valve sleeve may be temporarily retained in its discharge position, all as will appear more fully below.

Slidably mounted in the pump barrel 11, above the upper end of the pump cylinder 45 15, is a piston 35, which may be provided with suitable packing rings 36, and which is also provided with a suitable passage 37, leading from the under to the upper side thereof, which passage is controlled by a 50 suitable ball or other check valve, diagrammatically indicated at 38, which valve will permit the passage of fluid upwardly, but will prevent it in a return direction.

The said piston 35 is provided with a 55 downwardly extending hollow plunger 39, which slidably fits within the upper portion of the pump cylinder 15, as will be clear from Figs. 1 and 2. This plunger may also be provided with suitable packing rings 40 60 to afford a fluid tight joint with the walls of the pump cylinder.

The valve stem 24 extends upwardly into the interior of the said hollow plunger 39, passing through a removable guiding plug 65 41, which is provided with suitable fluid pas-

sages 42, surrounding the bore 43, through which the said valve stem passes, as is best shown in Figs. 2 and 5. The said stem 24 is provided at its upper end with an enlarged head 44, the outer periphery of which 70 may be cut away as indicated at 45 to permit the passage of fluid therearound. A coiled compression spring 46 surrounds the valve stem 24, resting upon the valve stem guide 31, as will be clear from Figs. 1 and 75 2, and a second coiled compression spring 47 also surrounds the said stem and rests upon the upper surface of the guiding plug 41.

The plunger 39 is provided, just below the piston 35 with the transversely extending holes or passages 48, affording communication between the annular chamber 16 and the passage 37 through the piston 35, 80 through which the oil from the pump may find its way into the portion of the pump barrel above the said piston 35. The upper end of the barrel 11 is closed by a suitable plug 49, which is provided with a passage 50 controlled by the ball or other check valve, diagrammatically indicated at 51. The said plug 49 carries the pipe or tube 52, which extends upwardly within the valve casing 10 to the surface, and which is provided with a suitable cap 53. A discharge pipe 54 leads from the said pipe 52 to a suitable tank or receptacle 55 mounted adjacent the outlet of the well, which tank is preferably provided with an overflow pipe 56 and with a suitable sand valve 57, as shown. A pipe 58 leads from the tank 55 to the inlet side of a pump 59, which may be driven from any suitable source of power not shown, and the outlet side of the said pump is connected by means of a pipe 60 to a receiver or pressure tank 61. A pipe 62 leads from the tank or receiver 61 and discharges into the interior of the valve casing 10, adjacent the top thereof, as clearly illustrated in Fig. 1.

The operation of the apparatus is as follows. Supposing the parts to be in the position shown in Fig. 1, if the pump 59 is operated to withdraw oil from the tank 55 and to transfer the same to the receiver 61, 115 thereby placing the oil under pressure, the said oil will be transferred from the receiver through the pipe 62 to the interior of the well casing 10, filling the annular space 13 between the said casing and the pump barrel. The said oil will pass through the pipes or passages 26 to and through the ports 29 of the valve sleeve 28 and will fill the interior of the pump cylinder, as will be readily understood.

The said oil will be prevented from escaping downwardly through the sand drain opening 22, due to the fact that the sand valve 23 is seated and its pressure will therefore be effective only to act upon the lower 130

surface of the trunk or plunger 39 to raise the same. A portion of the said oil will pass upwardly through the passages 42 around the valve rod 24 and into the interior of the hollow trunk or plunger, and will, after passing the notched head 44 of the valve stem, exert its pressure on the surface 65 of the said plunger.

The raising of the said plunger 39 will, 10 of course, raise the piston 35, working in the pump barrel 11, which will create a partial vacuum in the annular chamber 16 and will cause the oil from the well, which is below the pump unit, to be drawn upwardly 15 through the passage 18, past the check valve 19 and through the openings 20 into the said annular chamber 16, so long as the piston 35 ascends.

Just before the said piston 35 reaches the 20 upward limit of its stroke, the spring 47, which is being carried upwardly by the plunger 39 and plug member 41, will engage the lower surface of the head 44 of the valve stem 24, but the said spring is of such strength that it will not raise the said valve stem but will be compressed. As the upward movement of the plunger 39 continues however, the bushing or collar 66 will engage the said head 44, whereupon any further upward movement of the plunger 39 25 will be positively transmitted to the head 44 and valve stem 24 to raise the latter. This upward movement of the valve stem will, of course, unseat the sand valve 23, to permit any sand which has collected within the pump cylinder, to be discharged downwardly through the passage 22, and the said upward movement of the valve stem 24 will also carry with it the valve sleeve 28 to move 30 the ports 29 out of register with the passages 26, thereby cutting off the supply of fluid pressure from the annular space 13. The sleeve 28 will be moved upwardly a sufficient distance so that its lower edge will 35 clear the discharge ports 27, at which point the expansion ring 33 will enter the groove 34 formed on the interior of the cylinder walls to temporarily maintain the valve sleeve 28 in this raised position.

The discharge ports 27, having thus been opened, the fluid within the pump cylinder 15 will discharge through the said ports into the annular space 16, and when the pressure within the cylinder is thus relieved, the piston 35, together with its plunger 39, will descend under the action of gravity. This descent will continue, the valve sleeve 28, however, in the meantime, remaining in its raised or discharge position until the plug member 41 engages and compresses the spiral spring 46 to such an extent that its pressure will overcome the frictional resistance of the expansion ring 33 with the groove 34, to release the same, whereupon continued downward movement of the piston 35 and plunger

39 will carry with it the valve sleeve 28 to close the discharge ports 27 and again open the inlet ports 26 and 29.

The cycle will then be again repeated and the oil which has been drawn into the annular space 16 from the well, together with the oil which has been discharged into the said space from the pump cylinder, will be raised within the space 16 until it passes out through the passages 48 and 37 around the check valve 38 and into the upper portion of the pump barrel. As the strokes are multiplied, oil within this portion of the pump barrel will be forced upwardly, past the check valve 51, into the receiving pipe or tube 52, and thence through the pipe 54 into the tank 55. As the oil is accumulated in the said tank beyond that necessary for the operation of the pump mechanism, it is withdrawn by means of the pipe 56 for storage or further treatment.

It will thus be seen that this invention provides a pumping mechanism which is particularly adapted for use in deep wells, and which may be effectively operated to raise the oil without the use of sucker or polish rods, whereby the usual inherent defects and expenses attached to such rods may totally be eliminated. As above stated, two or more of these pumping units may be installed at various depths in the well, thereby permitting of the withdrawal of oil or of fluid from very deep wells. Any number of units may be simultaneously operated, each being fed by fluid under pressure from the annular space 13 and each raising the fluid from the well, together with the discharge actuating fluid, a considerable distance, until it reaches a point where it will be acted upon by the next succeeding unit.

The length of the stroke of the piston may be varied within wide limits, to suit various operating conditions, and the speed at which the pump may be operated is practically limited only by the speed at which the piston 35 will descend under the action of gravity.

Another important feature of the present pump resides in the following. In wells 115 wherein the gas pressure has lowered until it will not raise the oil within the casing, there is usually an accumulation of gas above the oil. This materially affects the operation of the usual pumps, inasmuch as 120 the accumulated gas acts as a cushion, preventing the creation of a vacuum below the piston, due to the compression and expansion of the gas. The compression occurs when the plunger goes down, and the expansion, when it rises, while the oil level 125 is not affected.

On the other hand, with the present pump, the oil which is exhausted from the pump cylinder through the ports 27 into the space 130

16, acts as an absorbent for this gas and carries it to the surface when the pump is operated, until all of the gas has been moved, when the oil from the well will be drawn 5 into the pump barrel in the manner above disclosed by the vacuum created by the piston 35.

While one form of the invention has been illustrated and described it is obvious that 10 those skilled in the art may vary the details of construction as well as the arrangement of parts without departing from the spirit of the invention, and therefore it is not wished to be limited to the above disclosure, except as may be required by the accompanying claims.

What is claimed is:

1. In a deep well pumping apparatus the combination with a well casing of a pump 20 barrel positioned within said casing and spaced from the walls thereof; a pump cylinder within said barrel, spaced from the walls thereof; a piston slidably mounted in said barrel and provided with a trunk extending 25 into said cylinder; fluid conducting connections between said cylinder and the space between said casing and said barrel; means for continuously supplying fluid under pressure to said last mentioned space; and means 30 for conducting fluid from said barrel.

2. In a deep well pumping apparatus the combination with a well casing of a pump 35 barrel positioned within said casing and spaced from the walls thereof; a pump cylinder within said barrel, spaced from the walls thereof; a piston slidably mounted in said barrel and provided with a trunk extending 40 into said cylinder; fluid conducting connections between said cylinder and the space between said casing and said barrel; a valve automatically operable by the movements of said piston and trunk, for controlling said fluid conducting passages; means for supplying fluid under pressure to 45 said last mentioned space; and means for conducting fluid from said barrel.

3. In a deep well pumping apparatus the combination with a well casing of a fluid 50 pressure pump including a barrel mounted within said casing in spaced relation to the walls thereof, a cylinder within said barrel, spaced from the walls thereof, and a piston slidably mounted in said barrel, having a trunk extending into said cylinder; fluid conducting connections between the interior of said cylinder and the space between 55 said casing and barrel; a closed conduit within said casing for conducting fluid from said barrel to the surface; and an external 60 pump and connections for supplying fluid under pressure continuously in one direction to the space between said casing and barrel.

4. A pump for deep wells comprising a barrel adapted to be inserted in a well casing 65 in spaced relation to the walls thereof;

a pump cylinder within said barrel, spaced from the walls thereof; a piston working in said barrel, provided with a trunk working in said cylinder; means for admitting fluid under pressure into said cylinder; and 70 a valve for controlling said admission, operable by the movements of said piston and trunk.

5. A pump for deep wells comprising a barrel adapted to be inserted in a well casing 75 in spaced relation to the walls thereof; a cylinder within said barrel, spaced from the walls thereof to provide an annular passage, and provided with outlet passages 80 affording communication between the interior of said cylinder and said annular passage; means for introducing fluid from outside of said barrel into said cylinder; a piston working in said barrel, provided with a trunk working in said cylinder; and 85 a valve in said cylinder for controlling the admission and exhaust of fluid thereto and therefrom, said valve being operable by movements of said piston and trunk.

6. A pump for deep wells comprising a 90 barrel adapted to be inserted in a well casing in spaced relation to the walls thereof; a cylinder within said barrel, spaced from the walls thereof to provide an annular passage, and provided with outlet passages 95 affording communication between the interior of said cylinder and said annular passage; means for introducing fluid from outside of said barrel into said cylinder; a piston working in said barrel, provided with 100 a trunk working in said cylinder; a valve in said cylinder for controlling the admission and exhaust of fluid thereto and therefrom, said valve being operable by movements of said piston and trunk; and means 105 for yieldingly retaining said valve in its exhaust position.

7. A pump for deep wells comprising a barrel adapted to be inserted in a well casing in spaced relation to the walls thereof; a cylinder within said barrel, spaced from the walls thereof to provide an annular passage, and provided with an interior annular groove and with outlet passages affording communication between the interior 115 of said cylinder and said annular passage; means for introducing fluid from outside of said barrel into said cylinder; a piston working in said barrel, provided with a trunk working in said cylinder; a valve in 120 said cylinder for controlling the admission and exhaust of fluid thereto and therefrom, said valve being operable by movements of said piston and trunk; and means comprising an expansion ring carried by said valve 125 and adapted to engage said groove for yieldingly retaining said valve in its exhaust position.

8. A pump for deep wells comprising a barrel adapted to be inserted in a well cas- 130

- ing in spaced relation to the walls thereof; a cylinder within said barrel, spaced from the walls thereof to provide an annular fluid conducting passage, said cylinder having fluid inlet passages leading from outside said barrel and outlet passages leading to said annular space; a plug having a passage therethrough, closing the lower end of said cylinder; a valved piston working in said barrel, provided with a trunk working in said cylinder; a valve stem slidably carried by said trunk, and provided with a valve for controlling said plug passage; and a cylinder valve sleeve slidably mounted on said valve stem, operable by movements of said piston and trunk for controlling said inlet and outlet passages.
9. A pump for deep wells comprising a barrel adapted to be inserted in a well casting in spaced relation to the walls thereof; a cylinder within said barrel, spaced from
- the walls thereof to provide an annular fluid conducting passage, said cylinder having fluid inlet passages leading from outside said barrel, and outlet passages leading to said annular space; a plug having a passage therethrough, closing the lower end of said cylinder; a valved piston working in said barrel, provided with a trunk working in said cylinder; a valve stem slidably carried by said trunk, and provided with a valve for controlling said plug passage; a cylinder valve sleeve slidably mounted on said valve stem, operable by movements of said piston and trunk for controlling said inlet and outlet passages; means carried by said valve sleeve for temporarily maintaining said sleeve in its exhaust position; and springs surrounding said valve stem for cushioning the movements of said sleeve.

ARTHUR C. TUNISON.
